UNITED STATES PATENT OFFICE.

CHESTER A. SIEGEL, OF ARLINGTON, NEW JERSEY, ASSIGNOR TO AMERICAN ARCH COMPANY, A CORPORATION OF DELAWARE.

ARCH BRICK.

Application filed December 31, 1921. Serial No. 526,126.

To all whom it may concern:

Be it known that I, CHESTER A. SIEGEL, a citizen of the United States, residing at Arlington, in the county of Hudson and 5 State of New Jersey, have invented certain new and useful Improvements in Arch Bricks, of which the following is a specification.

My invention relates to arches and arch 10 bricks, and especially to bricks for sectional fire arches such as are used in locomotive fire boxes, for example. I aim to adapt one style of brick to widely varying spans between circulation tubes or other 15 members supporting the arch, so that it may be unnecessary to keep on hand bricks of a great many different lengths; to prevent excessive or undesirable sagging of the brick forming an arch section or unit on 20 long spans; to facilitate the building up and taking down of the arch, by making it possible to do either one brick at a time; and to make the brick as stable as possible when used in side section construction. I 25 also aim to make the individual brick as strong and rugged as possible, so as to minimize breakage in manufacture, shipment, handling, etc.

How these and other advantages can be 30 obtained through my invention will appear from my description hereinafter of the best forms of embodiment known to me.

In the drawings, Fig. 1 as a fragmentary view showing a longitudinal section through 35 a locomotive fire box with an arch constructed according to my invention.

Fig. 2 shows a transverse section through the fire box, taken as indicated by the line 2—2 in Fig. 1.

Fig. 3 is a plan view of an arch unit on a larger scale than Figs. 1 and 2.

Figs. 4, 5 and 6 are fragmentary side views illustrating the adaptability of my type of brick to various spans.

Fig. 7 is a fragmentary view illustrating the behavior of an arch unit on a long span, on a still larger scale than Figs. 3 to 6.

Figs. 8 and 9 are fragmentary views, in 50 plan and in end elevation, respectively, showing an arch constructed according to my invention with a form of brick different from that of Figs. 1 to 7.

Fig. 10 is a bottom plan view of a single

brick such as shown in Figs. 8 and 9, on a 55 larger scale.

Fig. 11 is a fragmentary edge view of such a brick in engagement with a supporting water circulation tube as an abutment.

Fig. 12 is an edge view of such a brick resting directly on a water circulation tube at either end.

The fire arch 15 shown in Figs. 1 and 2 comprises a plurality of main spans or 60 sections supported by circulation tubes 17 extending lengthwise of the locomotive fire box 18, as well as lateral "half-span" sections 19 supported between the outermost tubes 17 and the side sheets 20 of the fire 65 box. Each of the main spans comprises a series of arch units 21 extending lengthwise of the fire box 18, and seen end-on in Fig. 2. Each of these arch units 21 (see Figs. 70 2 to 7) comprises a pair of refractory fire 70 bricks 22, 22 resting on the tubes 17 as supports or abutments and leaning against each other in the middle. For convenience, I shall refer to the portions of the fire 75 bricks 22 which rest on the supports 17 or 80 against one another as "ends," without reference to "length" or "breadth" as determined by the proportions of the bricks.

The outer end of each brick 22 is hollowed at its lower corner 23 (Figs. 4 to 7) 85 to enable the brick to rest and pivot securely on the support 17 (as shown, hollowed in a concave conforming to the cylindrical curvature of this support 17), and is reduced or bevelled at its upper corner 90 24. The inner end of each brick 22 has engagement means that cooperate with corresponding engagement means on the other brick of the arch unit pair in maintaining the two bricks in their reciprocally leaning 95 relation, yet permit the angular relation of the bricks to vary to adjust the effective length of the unit to varying spans or distances between the supporting tubes 17, 17. As shown, the bricks 22, 22 forming an 100 arch unit are similar; and as a whole, the interengaging ends of these bricks are exact counterparts of one another.

The engagement means of each brick 22 comprises a convex face 25 and a concave 105 face 26, each such face extending part (half) way across the end of the brick so as to engage the corresponding face of the

other sort on the other brick. The convex face 25 is on a projecting nose portion 27 at one side of the longitudinal center line of the brick, while the concave face 26 is at 5 the bottom (so to speak) of a recess portion 28. As shown, each of the faces 25 and 26 is substantially symmetrical in reference to the thickness of the brick, and the centers of figure of these faces substantially co- 10 incide in the midst of the brick,—i. e., about in the middle of its thickness. This latter feature allows the brick to be made with a shorter and stouter nose 27 and a shallower recess 28 than if the centers of figure of the 15 faces 25 and 26 were a substantial distance to either side of the median plane of the brick. The conformation and relative arrangement of the comparatively corresponding complementarily curved bearing faces 25 20 and 26 are such that in the arch unit they make multiple line or surface contact (as distinguished from mere single line contact), even in various reciprocally leaning angular relations of the cooperating bricks 25 on various spans. This extended contact causes the bricks 22, 22 of an arch unit to stick together over a considerable width and area as a result of superficial fusion in service, so that if the arch is afterward tempor- 30 arily taken down for any reason, these bricks will not break apart. As shown in Figs. 2 and 4 to 7, the surfaces 25 and 26 are semicircular (or semicylindrical) and of the same curvature, and their diameter 35 is substantially equal to the thickness of the brick at its inner end.

The upper and lower corners 31 and 32 of each concave face 26 are appropriately bevelled, reduced, or blunted, to minimize 40 breakage and fusion at these exceptionally weak and exposed points. At the upper end of the convex face 25, there is a shoulder 33 by which (so to speak) its circular contour is abridged or shortened. When the arch 45 unit is on normal or subnormal (short) spans, Figs. 4 and 5, the angular relation of the bricks 22, 22 is such that the shoulders 31 and 33 do not come in contact; but when the unit is on a supernormal (long) span of 50 sufficiently great width, the shoulders 31 and 33 engage or "interlock" as shown in Figs. 6 and 7, and thus prevent the unit from "sagging" unduly or dropping between the supports 17 if the span is further increased 55 slightly. Under the varying angular relations of the bricks 22, 22 corresponding to the very considerable range of span to which the bricks are intended to adjust and accommodate themselves, the strength of the 60 arch is substantially uniform.

As shown in Figs. 3 to 6, the bricks 22 are lightened somewhat by slag-retaining pockets 34, 34 in their lower sides.

The arch unit constitutes what may be 65 termed a three-hinged arch; and the pivot

point of the center hinge at 25, 26 moves up or down as the pivot points of the outer hinges shift inward and together or outward and apart, according to differences in span.

The sectional fire arch 40 illustrated in 70 Figs. 8 and 9 differs from the arch 15 of Figs. 1 and 2 in employing brick 42 that present important differences from the brick 22 and afford important advantages.

In the case of Figs. 8 to 12, the engagement means of one sort is divided, and located partly on opposite sides of intermediate engagement means of the other sort. That is to say, in the form of brick here shown the convex face 45 on the projecting 75 nose portion 47 is flanked at either side by duplicate concave faces 46, 46, at the bottom of duplicate recesses 48, 48. As shown, each of the concave faces 46, 46 and of the recesses 48, 48 has substantially half the width 80 of the convex face 45 and the nose 47. When, therefore, two such bricks 42, 42 are assembled as an arch unit, they do not overlap completely and lie directly opposite one another, as in Fig. 3; on the contrary, they 85 overlap but half way, so as to lie in a staggered relation to one another. In the middle arch section, therefore, each of the brick 42 (excepting only the extreme front and rear ones) is in effect paired in reciprocally 90 leaning engagement with two mates,—with each of which it forms an arch unit,—instead of with one only, as in Figs. 1-7. Hence this middle arch section consists of 95 a series of oppositely supported bricks multiply (doubly) intermated in reciprocally 100 leaning pairs. By virtue of this construction, all of the bricks 42 (except the first pair put in place) can be put in place or removed one at a time. With the bricks 22 105 of Figs. 1 to 7, no such possibility exists, because each of those bricks can be mated with but one other.

As shown in Figs. 10 to 12, each brick 42 has in its opposite edges, at the lower 110 side, recesses 49.

When the bricks 42 are assembled in an arch section, these recesses 49 in adjacent 115 bricks cooperate to form slag pockets separated by longitudinal ribs on the individual brick. This mode of providing the arch with slag pockets enables the bricks to be made strong and more rugged than if these pockets were complete in each brick, as in Figs. 3 to 6.

The bricks 42 of Figs. 8 to 12 presents a further advantage over the brick 22 of Figs. 1 to 7, in that when the brick 42 is used to form a lateral half arch (Fig. 8 and 9) resting against a side sheet 20 of the fire box it is more stable, owing to the fact that its nose portion 47 which then engages the side sheet 120 is in its middle instead of to one side thereof. The like is true when the brick 42 is used to form a half arch between two sup-

ports such as the tubes 17 in Fig. 12, so that the rounded surface 45 of the nose 47 rests on a tube 17.

In Figs. 8 to 12, various parts and features substantially like corresponding ones in Figs. 1 to 7 have been marked with the same reference numerals as in Figs. 1 to 7, as a means of avoiding merely repetitive description.

10. If desired, half brick 52 (similar in general form to the brick 22 of Figs. 1 to 7) may be employed to fill gaps that would otherwise exist in the arch 45, as shown in Fig. 8.

15. What I claim is:

1. An arch brick having on one end convex and concave faces, each symmetrical as regards the thickness of the brick, for engagement with correlative corresponding concave and convex faces of another brick in various reciprocally leaning angular relations of such bricks on various spans.

2. An arch brick having on one end convex and concave faces with coincident centers of figure in the midst of the brick, so that the brick may lean stably against another brick, in various angular relations on different spans, by engagement of its aforesaid faces with correlative corresponding concave and convex faces of such other brick.

3. An arch brick having on one end convex and concave faces of diameters substantially equal to the thickness of the brick with coincident centers of figure in the midst thereof, for engagement with correlative corresponding concave and convex faces of another brick in various reciprocally leaning angular relations of such bricks on various spans.

4. An arch brick having on one end convex and concave faces, with centers of figure in the midst of the brick, adapted to make multiple line contact, respectively, with correlative corresponding concave and convex faces of another brick in various reciprocally leaning angular relations of such bricks in various spans.

5. An arch brick having on one end convex and concave semicircular faces of the same curvature, with centers in the midst of the brick, adapted to make surface contact with correlative corresponding complementary faces of another brick in various reciprocally leaning angular relations of such bricks.

6. An arch brick having on one end convex and concave semicircular faces of the same curvature, concentric with one another and with the thickness of the brick, for making surface contact with correlative corresponding counterpart faces of another brick in various reciprocally leaning angular relation of such bricks.

65. 7. A self-adjusting arch brick unit com-

prising counterpart arch brick having at one end correlative recess and projecting nose portions, with rounded concave and convex bearing surfaces of the same curvature with their centers of figure in the midst of the brick.

8. An arch brick having on one end convex and concave faces for engagement with correlative corresponding concave and convex faces of another brick in various reciprocally leaning angular relations of such bricks on various spans, and having shoulders adjacent such faces for engaging with corresponding shoulders on such other brick to prevent undue sagging of the brick on long spans.

9. A brick for sectional fire arch construction having on one end engagement means of one sort flanked at either side by engagement means of a different sort, so that the brick may lean stably against one or more similar brick by engagement of its flank engagement means with the intermediate engagement means of such other brick or bricks, and vice versa.

10. A sectional fire arch construction comprising an arch brick having at one end an intermediate projecting nose portion with recess portions each of substantially half its width flanking it, said nose and recess portions being in leaning engagement, respectively, with the correlative flank and nose portions of one or more similar brick.

11. An arch brick having at one end a convex faced intermediate projecting nose portion and concave faced recess portions flanking it at either side, for leaning engagement with the correlative flank and nose portions, respectively, of one or more similar bricks.

12. An arch brick having on one end convex and concave faces, including an intermediate face of one sort flanked, at either side, by faces of the other sort, so that the brick may lean stably against one or more other such brick, in various angular relations on different spans, by engagement of its flank face or faces with the intermediate face or faces of such other brick or bricks and engagement of its intermediate face with the flank face or faces of such other brick or bricks.

13. An arch brick having on one end a convex intermediate face and concave faces flanking its at either side, so that the brick may lean stably against one or more other such bricks, in various angular relations on different spans, by engagement of its convex face with the concave face or faces of such other brick, and vice versa.

In testimony whereof, I have hereunto signed my name.

CHESTER A. SIEGEL.
